SHOE CONSTRUCTION

Ernst J. Story and John M. Delaney,
Cincinnati, Ohio

Application October 24, 1933, Serial No. 694,966

1 Claim. (Cl. 36—34)

This invention relates to shoe construction, and particularly to a manner and means for anchoring the flap of the sole in the region of the heel.

An object of the invention is to provide simple, 5 inexpensive, and effective means for anchoring the flap of the sole, while at the same time enhancing the appearance of the shoe.

Another object is to provide a heel of novel construction including means for effectively 10 holding the flap of the shoe sole.

These and other objects are attained by the means described herein and disclosed in the accompanying drawing, in which:

Fig. 1 is a side elevation of a shoe embodying 15 the invention.

Fig. 2 is a top plan view of the heel of this invention.

Fig. 3 is a side elevational view of the heel of Fig. 2.

Fig. 4 is a perspective view of a shoe sole and showing the flap to be held in position by the novel heel construction.

The present invention is directed to a solution of the problem of securely and inexpensively 25 fastening a finishing flap, such as is indicated at 5, relative to the heel of an article of footwear. Those persons concerned with the manufacture of shoes have long been confronted with the problem of precluding loosening or peeling of 30 the flap from its position adjacent to the breast of the heel, however, no satisfactory solution of the problem has been proposed heretofore.

Referring now to the accompanying drawing, the character 6 indicates generally a shoe having a sole 7 and a heel 8. The rear end 9 of the leather strip of which the sole is made, rests upon and is suitably secured to the foot-supporting face 10 of the heel 8. At a location forwardly of the breast 12 of the heel, the rear end of the 40 sole strip or sheet is slotted flatwise transversely of said strip or sheet, to provide the thin integral flap 5 which provides a means of neatly finishing off the under portion of the shoe in the region of the breast of the heel.

The heel 8 preferably, though not necessarily, 45 is of one-piece construction and may conveniently be made of wood properly formed. The upper foot supporting portion 10 preferably has formed integrally therewith an extension 13 which over- 50 hangs the breast portion and meets the breast portion along a line of juncture which is slotted

as at 14 to provide a channel for reception of the flap 5. The slot extends transversely of the breast portion from one side of the heel to the other. The foot-supporting portion 10 is a concavity in the top of the heel, which extends 5 lengthwise of the extension 13, wherefore the lower face 15 of the extension is made convex. The slot or channel 14 therefore is curved downwardly and inwardly from the sides of the heel. It is to be understood, however, that it is immaterial to the invention whether or not the channel is curved, for on some types of shoes the slot may be extended straight across the breast of the heel near the top thereof.

In constructing the shoe, the upper is secured to 15 the sole and to the heel portion 9 thereof, after which flap 5 is disposed over the extension 13 and inserted into the channel or slot 14, where it may be glued or otherwise suitably secured. The flap may be glued or otherwise secured to the extension 20 13 in order to afford a finished appearance to the arch portion of the shoe. After thus securing the parts together, the heel ordinarily is covered, painted or otherwise finished. The lower face 16 of the heel, if desired, may have a lift 25 applied thereto in accordance with common practice.

What we claim is:

A one-piece wooden high heel comprising a body having a dished upper face and including 30 a high substantially flat and vertical breast bounded at its upper end by a curved slot cut horizontally into the body of the heel, the opposite ends of said slot terminating in the sides of the body below the top edges thereof, at a higher elevation than the lowest point on the dished upper face, an extension on the heel body, forming part of the dished upper face of the body, and extending forwardly substantially at right angles to the plane of the breast, said extension having 40 a curved under surface which is a straight-forward continuation of one wall of the slot, said surface being curved transversely to conform substantially with the curvature of both the slot and the dished upper face, to provide substantially 45 a curved knife-edge on the extension, all points of which edge are located in a plane substantially parallel to the plane of the breast.
